UNITED STATES PATENT OFFICE.

ROBERT S. GRAHAM, OF NEW YORK, N. Y., ASSIGNOR OF ONE-HALF TO WILLIS M. FOLLMER, OF NEW YORK, N. Y.

RESILIENT CAP FOR THE KEYS OF TYPEWRITERS OR SIMILAR MACHINES.

Application filed May 17, 1924. Serial No. 713,941.

To all whom it may concern:

Be it known that I, ROBERT S. GRAHAM, a citizen of the United States, residing in the city, county, and State of New York, have 5 invented certain new and useful Improvements in a Resilient Cap for the Keys of Typewriters or Similar Machines, of which the following is a full, clear, and exact description, such as will enable others skilled 10 in the art to which it appertains to make and use the same.

This invention relates to a resilient cap for the keys of typewriters, or similar machines, and the objects of the invention are 15 to provide a resilient or cushioned cap that is interchangeable without reference to the index letter or numeral of the key to which it is to be applied. Further objects of the invention are to provide a cap that will, 20 when applied to a key, have a dish shaped top provided with cushion members surrounding an opening, said cushion members being provided with cushion supports adjacent said opening which will act to permit of the cushion members being progressively flexed to provide a resilient cushioning effect to the fingers of the operator. Referring to the drawings:

Figure 1 is a perspective view of the key 30 end of a key bar of a typewriter, or similar machine, provided with a resilient cap made in accordance with the invention.

Figure 2 is an enlarged top view of Fig. 1.

Figure 3 is a sectional view on the line 35 3—3 of Fig. 2.

Figure 4 is a sectional view on the line 4—4 of Fig. 2.

Figure 5 is a bottom view of the cap.

In the drawings 1 designates the key end 40 of an ordinary typewriter bar, or key end of any similar machine, which is provided in the present instance with the usual key comprising a circular disk 2 having on its upper surface an index letter or numeral, the same being covered with a circular disk 3 of glass, both supported on a metal key base 4 having an upturned edge 5 and a shank 6 secured to the upturned portion of the key bar. The disks 2 and 3 are held in 45 position on the top of the key base 4 by means of a circular flange 7 surrounding the outer edge of the upturned edge 5 and crimped over the top thereof, and the circumferential edges of the disks 2 and 3 so 55 as to provide a circular beaded edge 8.

The beaded edge 8 of the circular flange 7 forms a continuous bead or ridge about the upper surface of the key not only to secure the parts of the key together but also to provide a suitable working surface for the 60 fingers of the operator to prevent slipping, the circumferential bead or ridge 8 extending upward above the surface of the key to accomplish this purpose.

The typewriter key above described is 65 similar to the typewriter keys in use on a great variety of typewriters and similar key operated machines and is adapted to be covered by a removable resilient rubber cap 9 made in accordance with the present in- 70 vention.

The typewriter key cap 9 is, in accordance with the present invention, preferably made of rubber suitably molded to provide a hollow disk shaped cap comprising a cylindrical body 10, the inner diameter of which is less than the outer diameter of the key, the key cap being open at the bottom and provided with an inner guide flange 11, the inner edge of which is cut to flare outward as 75 shown at 12 to facilitate the key cap being forced over the top of the key after which the guide flange 11 assumes normal locked position against the bottom of the key as 80 shown in Fig. 3 and Fig. 4. 85

The key cap 9 is also, in accordance with the present invention, provided with a flat top, or slightly dished top, having side and end cushion members 13 and 14, which surround a top opening so as to make visible the 90 index letter or numeral on the disk 2. In the present instance the top opening in the key cap 9 is made greater in length than in breadth, the greater length being in the direction of the key bar to more easily show the index letter or numeral, although if desired the top opening can be made round or other convenient shape to expose the index letter or numeral; however, the elongated opening as shown in the drawings is to be 95 preferred.

The side and end cushion members 13 and 14 are preferably made of uniform thickness and preferably thicker than the sides of the cylindrical body portion 10. In the present 105 instance the end cushion members 14 extend slightly over the beaded edge 8 of the key and rest upon the same, as shown in Fig. 3, whereas, the side cushion members 13 extend a considerable distance over the beaded 110

edge 8 of the key, the outer edge resting upon the same while the inner edge of the cushion members are provided with integral supports 15 which rest upon the upper surface 5 of the glass disk 3, as shown in Fig. 3 and Fig. 4.

In the present instance the supports 15 are preferably made quarter-spherical in shape in order to provide progressively increasing resistance as the same are forced downward by the finger of the operator. The supports 15 act to normally keep the inner edges of the side cushion members 13 from sagging, and as the top of the cap is struck the same spreads or flattens out to provide progressively increasing resistance. The supports 15 in the present instance do not completely cover the underside of the side cushion member 13 but are spaced away 20 from the beaded edge 8 of the key, the supports 15 are also tapered away from the inner edge of the opening in the cap, as well as being tapered in both directions along the side of the opening, as clearly 25 shown in the drawings.

In order to make the top of the key cap more resilient and also to provide a greater view of the index letter or numeral on the key, the inner edges of the side cushion members 13 and the supports 15 are suitably beveled or undercut as shown at 16. The undercutting of the inner edges of the side cushion members permits of the opening in the top of the cap being made relatively small without obstructing to any great extent a clear view of the index letter or numeral on the key; the same also acts to obviate glare or reflection of light from the surface of the key, besides giving a certain resiliency to the top of the cap when struck by the finger of the operator, due to the overhanging portions of the side cushion members, the supports 15 acting to progressively cushion the blow as the key is forced downward, to give a relatively firm 45 resilient touch.

A key cap made as above described will, when forced over the top of a key, act, by reason of the raised beaded edge 8 on the circumference of the key, to become dish shaped with the lowermost edge of the supports 15 resting upon the upper surface of the glass disk 3. The dish shape of the top of the key cap is caused not only by the fact that the same may have a preliminary dish shape when molded, but also to the fact that the inner circumference of the body portion 10 being less than the outer circumference of the key acts to dish the cap at the centre which it is permitted to do as the ends of the supports 15 are arranged to be of sufficient depth to permit of the central portion of the cap being dished before the supports rest upon the top of the glass disk 3 of the key.

From the above description it will be seen that a resilient cap is provided which can easily be forced over, or removed from, the top of a key for a typewriter, or similar machine, and that the same will in view of its construction provide a dish shaped top, or working surface, that will permit of the same being progressively flexed by the finger of the operator to progressively cushion the blow when struck.

While the invention has been described with particular reference to the details of construction, the same is not to be considered as limited thereto as many changes can be made and still fall within the scope of the invention set forth in the following claims.

What I claim is:

1. A resilient cap for typewriter and similar keys provided with an upwardly extending circumferential ridge, said cap being made in the form of a hollow disk having a top opening, side cushion members adjacent said top opening, and supports secured to said side cushion members, said cushion members and supports being tapered from the edge of said top opening inward toward the ridge of said key as well as being tapered in opposite directions along the side of said opening, said supports being arranged to engage the top of 95 said key when the cap is forced over the top of said key.

2. A resilient cap for typewriter and similar keys comprising a top and integral circular flange of elastic material, the said top being formed with a slot; elastic supporting members depending from the underside of said top adjacent the slot therein, the said supporting members being of quarter-spherical shape and adapted for contact 100 with the face of a key over a small area at either side of said slot.

3. A resilient cap for typewriter and similar keys provided with an upwardly extending circumferential ridge, the said cap comprising a circular flange of elastic material and a top integral therewith, the said top being composed of front and rear flanges and side cushion members defining a slot in the center of said cap, the front and rear flanges being adapted to rest on the circumferential ridge of the key; depending supports integral with said side cushion members and adjacent the slot, the said supports being of quarter-spherical 115 shape and adapted for contact with the face of a key over a small area at either side of said slot.

In testimony whereof I have signed this specification in the presence of two subscribing witnesses.

ROBERT S. GRAHAM.
